DOOR LOCK

Frederick Noel Robertson, Vancouver, British Columbia, Canada

Application April 20, 1936, Serial No. 75,377

5 Claims. (Cl. 292—169)

My invention relates to improvements in door locks which are particularly adapted for use on motor cars. The objects of the invention are to provide means for opening and closing and locking a door from within or without; to provide an operating handle for the outside of the door which can be rendered inoperative from within and can be made free to move in either direction when rendered inoperative. Further objects are to provide a lock which will permit the glass of a motor car door to extend close to the door stile through which the latch bolt projects, and also to provide a lock of rigid design which will be extremely cheap to manufacture.

The invention consists of a lock having a latch bolt, an outer and inner handle each capable of withdrawing the latch bolt, means operable by the inner handle for rendering the latch bolt inoperative by the outer handle, said outer handle being mounted for substantially horizontal movement towards the striking plate of the lock to withdraw the latch, as will be more fully described in the following specification and shown in the accompanying drawings, in which:—

Fig. 1 is a sectional view of the lock with the front cover plate removed.

Fig. 2 is a plan view taken on the line 2—2 of Figure 1.

Fig. 3 is a detail view of the stop mechanism applicable to the lock shown in Figures 1 and 2 to prevent free movement of the outer handle when said handle is rendered inoperative.

Fig. 4 is a sectional view of a modified form of the invention.

Fig. 5 is a plan view taken on the line 5—5 of Figure 4.

Fig. 6 is a transverse sectional view taken on the line 6—6 of Figure 5.

Fig. 7 is a detail view showing the means for rendering the outer handle of the lock shown in Figures 4, 5 and 6 freely movable when the latch bolt is locked.

Fig. 8 is a sectional view showing the stops on the inside handle.

Fig. 9 is a modification of the inside locking means as applied to the structure shown in Figures 1, 2 and 3.

Fig. 10 is a modification of the inside locking means as applied to the structure shown in Figures 4, 5, 6 and 7.

In the drawings like characters of reference indicate corresponding parts in each figure.

The numeral 1 indicates a door having an outer panel 2, an inner panel 3 and a stile 4 be-

tween which is supported a glass guide channel 5 and a vertically movable glass panel 6. The outer panel is provided with an opening 7 through which access is obtained to operate the door lock generally indicated by the numeral 8. The lock 8 is provided with outer and inner plates 9 and 10 respectively, which journal between them a horizontal shaft or spindle 11. A guide 12 is formed on the plate 10 in which a latch bolt 13 is slidably movable. The latch bolt 13 is urged in an outward direction by a spring 14 and is provided with two inwardly extending pins 15 and 16.

The usual inner handle 17, shown in chain dotted line in Figure 8, is fitted to the inner panel 15 3 and is provided with a spindle 18, a crank disc 19 notched as at 20 to receive a spring stop 21 when moved to normal and locked positions. Connected to the crank disc 19 is a bar 22 provided with a slot 23 at its outer end through 20 which the pin 15 on the latch bolt extends. The outer end of the bar 22 is inwardly turned to form an abutment 24. A light spring 25 extends between the inner end of the latch bolt 13 and the outer end of the bar 22 to hold the outer 25 end of the slot 23 in contact with the pin 15, so that a downward movement of the inner handle 17 from normal position will cause the bar 22 to move inwardly and retract the bolt.

Mounted upon the spindle 11 is a finger 26 provided with two abutments or points of thrust which are respectively numbered 27 and 28, the abutment 27 being adapted to engage the pin 16 and the abutment 28 being adapted to be engaged by the abutment 24 of the bar 22.

An outer handle 29, having a horizontal bar 30, is swingingly mounted upon pivot pins 31 and 32 from arms 33 and 34, which are pivotally connected from the outer plate 9, so as to provide an endwise movement of the handle towards the stile 4 to open the lock. This handle is mounted at the marginal edge of the opening 7 so that to engage it the fingers are inserted through the opening and the handle is moved behind the outer lock plate 9.

Swingingly mounted from the pin 31 is a push rod 35 which is downwardly urged by a spring 36, shown in dotted line in Figure 1. This spring is passed around the pin 32 and up to engage the arm 34, thus serving also to urge the handle 29 back to normal position as shown. The free end of the push rod 35 is cut away on its lower edge to provide an abutment 37 and an overlying tongue 38.

Secured adjacent the outer end of the spindle 55

11 is an L-shaped lever 38 having an offset lug 40 at its heel and a further lug 41 at its toe. The lug 40 is engaged by the abutment 37 when the handle 28 is pushed forwardly and the push rod 35 is raised out of operative engagement when the L-shaped lever 38 is swung beyond normal position in a clockwise direction as shown in dotted line as at M, and when so raised, the handle is free to be moved without operating the latch bolt as the abutment 37 will be raised above the lug 40. Mounted in the outer side of the lock is a lock cylinder 42 having a cam 43, shown in dotted line in Figure 1, which on being turned to locking position raises the push rod 35 out of engagement with the lug 40, as shown in dotted line as at N. Should it be desired to prevent free movement of the handle 28 when the operative connection between said handle and the L-shaped lever 38 is broken, a projection 44 is formed upon the upper edge of the push rod 35, as shown in Figure 3, which is provided with a back stop 45 both of which engage a lug 46 extending inwardly from the outer lock plate 8 when the push rod 35 is raised either by movement of the inner handle or the turning of the cam 43 of the lock cylinder 42 to raised position.

In the modification shown in Figures 4, 5, 6 and 7 the latch bolt 13 is slotted adjacent its inner end as at 50 and the bar 22 operated by the inner handle is provided with a pin 51 passing therethrough. The free end of the bar 22 is provided with a lug 52 which projects below the latch and is adapted to engage, when being moved towards the stile 4 of the door, the upper end 53 of a bell crank 54. This bell crank is pivoted upon the inner plate 10 of the lock and has a horizontal leg 55 which is adapted to engage one end of a rocking lever 56, see particularly Figure 6. The rocking lever 56 is provided adjacent the outer side of the lock with a horizontal member 57 which on being raised is interposed between the lower end of the arm 34 and the stile 4 to prevent said arm from swinging.

The lock cylinder 42 in this modification is disposed immediately below the horizontal member 57, so that on being turned to locking position the lock cam 43 raises the horizontal member in the same manner as the rocking of the bell crank 54.

50 When it is desired to make the handle 28 freely movable and at the same time inoperative to retract the latch bolt the horizontal bar 30 of the handle is provided with a horizontal slot 58, shown in dotted line in Figure 4, through which the pivot pin 32, which is carried by the arm 34, extends.

55 Pivotedly mounted upon the pivot pin 31 is a link 59 urged downwardly by a light spring 60 and having a slot 61 extending horizontally and terminating with a vertical offset 62 in which the pivot pin 32 normally is engaged. The horizontal member 57 is provided with a lug 63 which projects under the free end of the link 59, so that when said link is raised by the rocking lever 56 the slot 61 of the link and the slot 58 of the horizontal bar 30 of the handle are brought into register with each other, so that the pin 32 and its arm 34 are held against movement and the handle and its horizontal bar 30 are free to move endwise against a spring 64 without rocking the spindle 11. The upper end of the bell crank 54 is held in engagement with the lug 52 by a light spring 65.

70 Where it is preferred to use a push button on the sill of the door for rendering the outer handle

inoperative, the inner handle 17 is arranged to move to withdraw the latch bolt 13 and to have no locking function.

75 In the modified locking means shown in Figure 9 a bell crank 66 is mounted upon a pivot pin 67. The bell crank is provided at its lower extremity with a lug 68 and is connected at the free end of its horizontal leg 69 with a push rod 70 projecting through the door sill 71 and fitted with a button 72. The push rod is provided with lower and upper grooves 73 and 74 which are adapted to be engaged by a suitable spring stop 75. When the button 72 is in raised position as shown, the outer handle is operative and when the button is pressed downwardly to cause the spring stop 75 to engage the upper groove 74 the lug 68 will engage the finger 26 and rock the shaft 11 in a clockwise direction to the limit of its stroke.

80 In the modified locking means shown in Figure 10 the push rod 70 connects with a lever 76 which in turn is connected at its free end through a hooked member 77 to the free end of the rocking lever 56 so that as the button 72 is pressed downwardly to the limit of its stroke, the rocking lever 56 is moved to dispose its horizontal member 57 between the lower end of the arm 34 and prevent said arm from being so swung towards the stile 4 of the door.

85 In operating the lock as shown in Figures 1, 2 and 3 from the inside the inner handle is pressed down in the usual way, which pulls the bar 22 rearwardly and through the pin 15 retracts the latch bolt 13 against the thrust of the spring 14. When the inner handle is raised above its normal position the bar 22 is thrust forwardly, its abutment 24 engaging the abutment 28 of the finger 26, thus rocking spindle 11 in a clockwise direction and raising the L-shaped lever 38 so that the push rod 35 is raised out of engagement with the lug 37 of the lever 38, hence the outer handle 28 may be moved towards the free edge of the door without operating the latch. When the lock cylinder 42 is turned to raise its cam 43, the push rod 35 is likewise raised, so that the movement of the handle 28 will not operate the latch bolt 13. The disengagement between the push rod 35 and the L-shaped lever 38 is identical whether effected by the inner handle or the lock cylinder.

90 Where the push rod 35 is provided with a stop 45 as shown in Figure 3, the push rod when raised, either by the lock cylinder movement or from the upward movement of the inner handle, will be out of engagement with the L-shaped lever 38, but the stop 45 being brought into engagement with the lug 46 will prevent the outer handle 28 from being moved. When the outer handle is not in inoperative position its movement towards the free edge of the door causes the push rod 35 to engage the lug 37 of the L-shaped lever 38 and rock the spindle 11 in an anti-clockwise direction, thus swinging the finger 26 to bear upon the pin 16 and thrust the latch bolt 13 rearwardly to retract it from engaging position.

95 In the operation of the lock as shown in Figures 4, 5, 6 and 7 the door is opened from the outside by moving the outer handle 28 in a similar manner to that above described. If the lock cylinder 42 is turned to dispose its cam 43 upwardly the rocking lever 56 is tipped, raising its horizontal member 57 to prevent the swinging movement of the arm 34 and to lift the link 59 that the outer handle may have free and inoperative movement. The operation of the inner handle is also as previously described, but on being raised above normal position it causes the bar 22 to move forwardly to rock the bell crank 54 and tip 76

the rocking lever 56 to stop the swinging movement of the arm 34, so that again the outer handle is rendered inoperative.

It will be preferred that neither of the button locking means shown in Figures 9 and 10 be used on the doors which are fitted with key locking means. On the door locks where key means are not employed the general function of the several parts will remain unchanged except that the inner handle will not be used necessarily for the purpose of rendering the outer handle inoperative.

What I claim as my invention is:

1. A door lock having a latch bolt, an outer and an inner handle for retracting the latch bolt, a rock shaft having a finger adapted to engage the latch bolt and a lever, a push rod carried by the outer handle adapted to normally abut the lever, and means for preventing the push rod from abutting the lever whereby the outer handle is rendered inoperative.

2. A door lock having a latch bolt, an outer and an inner handle for retracting the latch bolt, a rock shaft having a finger adapted to engage the latch bolt and a lever, a push rod carried by the outer handle adapted to normally abut the lever, and means for raising the push rod out of abutting contact with the lever whereby the outer handle is rendered inoperative.

3. A door lock having a latch bolt, an outer and an inner handle for retracting said latch bolt, a spindle operatively connecting the outer handle to the latch bolt, and means as the inner handle is turned in an abnormal direction for disrupting the connection between the outer handle and the spindle and for preventing the movement of the outer handle.

4. A door lock having a latch bolt, a spindle, a finger extending from the spindle adapted to engage the latch bolt to retract it, an outer and an inner handle, said outer handle being connected to the spindle to rock it, a bar extending from the inner handle and slidably engaging the latch bolt, and means on said bar adapted as the handle is turned in an abnormal direction for engaging the finger to rock the spindle and disrupt the connection between the outer handle and said spindle.

5. A door lock having a plate, a spindle rockingly mounted transversely to the plate, a latch bolt adapted for retraction in response to the rocking of the spindle, a pair of arms swingingly mounted from the plate, a handle supported from the free ends of the arms, and means normally connecting the handle with spindle to rock it.

FREDERICK NOEL ROBERTSON.
